(57) **CLAIM**

The ornamental design for a plumber's pad, as shown and described.

DESCRIPTION

FIG. 1 is a front perspective view of a plumber's pad, showing new design;

FIG. 2 is a front perspective view in the open position;

FIG. 3 is a top plan view of FIG. 1;

FIG. 4 is a bottom plan view of FIG. 1;

FIG. 5 is a front elevational view of FIG. 1;

FIG. 6 is a rear elevational view of FIG. 1;

FIG. 7 is a right side elevational view of FIG. 1; and,

FIG. 8 is a left side elevational view of FIG. 1.

The broken lines shown on the plumber's pad represent stitching.
